Watson E. Coleman
Attorney

UNITED STATES PATENT OFFICE.

ISAAC GEABES, OF PATRICKSBURG, INDIANA.

MINE TOOL.

Application filed May 20, 1924. Serial No. 714,699.

To all whom it may concern:

Be it known that I, ISAAC GEABES, a citizen of the United States, residing at Patricksburg, in the county of Owen and State 5 of Indiana, have invented certain new and useful Improvements in Mine Tools, of which the following is a specification, reference being had to the accompanying drawings.

10 This invention relates to mine tools and more particularly to a mine blasting scraper and scoop adapted for use in cleaning the charge receiving bores formed in coal mines.

An important object of the invention is 15 to provide a device of this character which is extensible, so that it may be shortened for work in close quarters and extended from time to time to permit its use in withdrawing the contents of bores of considerable 20 length.

A still further object of the invention is to provide a device of this character the extensible construction of which is such that it may be employed for making the necessary rough measurements for timbers employed in timbering mines.

A still further object of the invention is to provide a device of this character which may be cheaply and expeditiously produced 25 and handled, which will not clog from the dirt and dust with which it is necessarily associated and which is a general improvement in the art.

These and other objects I attain by the 30 construction shown in the accompanying drawings, wherein for the purpose of illustration is shown a preferred embodiment of my invention and wherein:

Figure 1 is a perspective view of a tool 35 constructed in accordance with my invention;

Figure 2 is a longitudinal sectional view therethrough.

Referring now more particularly to the 40 drawings, the numerals 10 and 11 indicate telescopically engaged handle portions, the section 10 being in the form of a tube and the section 11 in the form of a small solid bar closely fitting the bore of the tube and 45 slidable therein. To one end of the tube is brazed a scoop 12 curved on a diameter equal to the diameter of the hole usually formed for the reception of a blasting charge. The free end of the section 11 is 50 flattened and bent at an angle to provide a

scraper 14 preferably circular in form and of slightly smaller diameter than the diameter of the hole formed in such blasting.

In the construction of the device and in the formation of the scraper the end of the tube 10 is preferably split for a short distance and forged into a semi-circular shape corresponding to the shape of the scraper which is then welded or brazed to this forged portion as indicated at 15. The rod 11 has formed therein at uniformly spaced intervals sockets 16 for the reception of the ends of a spring catch 17 which projects through an opening in the wall of the tube 10 and has an attaching portion 18 forming the spring of the catch attached to the outer surface of the tube. It will be obvious that by uniformly spacing these openings, when the latch is engaged in a given opening, the overall length of the tool may be readily determined, thus enabling the use of the device for rough measurements as above set forth. In cleaning a blast bore the scraper is used to withdraw such of the contents as can be so withdrawn, the remainder of the 60 contents which are forced to the rear of the bore by the scraper being removed by the use of the scoop.

Since many changes are possible in the general construction without materially departing from the spirit of my invention, I do not limit myself to such specific structure as hereinbefore set forth except as herein-after claimed.

I claim:

1. A mine tool of the character described comprising a pair of telescopically engaged handle sections, the outer section having secured to its free end a scoop, the free end of the inner section being flattened and bent at an angle to provide a scraper.

2. A mine tool of the character described comprising a pair of telescopically engaged handle sections, the outer section having secured to its free end a scoop, the free end of the inner section being flattened and bent at an angle to provide a scraper, a spring latch extending through the wall of the outer member and selectively engageable in sockets formed in the inner member, said sockets being uniformly spaced.

In testimony whereof I hereunto affix my signature.

ISAAC GEABES.
